CLAIM

The ornamental design for a tail lamp, as shown and described.

DESCRIPTION

FIG. 1 is a perspective view of a first embodiment tail lamp in accordance with the present invention, wherein a perspective view of a second embodiment tail lamp in accordance with the present invention is a mirror image thereof;

FIG. 2 is another perspective view of the first embodiment tail lamp, wherein another perspective view of the second embodiment tail lamp is a mirror image thereof;

FIG. 3 is yet another perspective view of the first embodiment tail lamp, wherein yet another perspective view of the second embodiment tail lamp is a mirror image thereof;

FIG. 4 is a left side elevation view of the first embodiment tail lamp, wherein a right side elevation view of the second embodiment tail lamp is a mirror image thereof; and,

FIG. 5 is a front side elevation view of the first embodiment tail lamp, wherein a front side elevation view of the second embodiment tail lamp is a mirror image thereof.

The back, bottom and right side views of the first embodiment tail lamp and the back, bottom and left side views of the second embodiment tail lamp form no part of the claimed design.

1 Claim, 5 Drawing Sheets
